UNITED STATES PATENT OFFICE.

JAMES M. FINNELL, OF OMAHA, NEBRASKA, AND ERNEST P. GREVE, OF SHELBY, IOWA.

DAMPER FOR OIL-BURNING STOVES.

Application filed September 21, 1925. Serial No. 57,678.

The invention relates to dampers for oil burning stoves, and has for its object to provide means for producing more heat per unit of oil consumed than is possible in any other 5 manner and producing a constant and absolutely uniform heat at all times.

A further object is to provide a damper suspended in the stove above the oil burner on a shaft extending through the combustion 10 chamber and disposed on bearings on either side of the combustion chamber casing. Means are provided for adjusting the damper vertically in the casing in which the shaft carrying the damper is disposed and consisting of vertical slots through which the shaft 15 bearings will pass, the damper being held in different positions by locknuts disposed on the shaft on either side of the casing, thereby allowing the damper to be adjusted 20 vertically according to the draft of the chimney or smoke shaft.

Another object of the adjustable mounting of the damper is that it may be set sufficiently close to the burner to retain the heat 25 generated by the burner in the lower part of the combustion chamber and eliminate waste by preventing the heat from passing up the stove pipe or smoke stack.

With the above and other objects in view 30 the invention resides in the combination and arrangement of parts as hereinafter set forth, shown in the drawing, described and claimed, it being understood that changes in the precise embodiment of the invention may be 35 made within the scope of what is claimed without departing from the spirit of the invention.

Referring to the drawing wherein the single figure is a perspective view of the stove, 40 the numeral 1 designates a conventional form of stove and 2 the door thereof which is supported on legs 3 and is provided with a stove pipe 4 used in connection with stoves of limited size and 5 an oil supply tank. 45 In larger stoves larger supply tanks are used and are usually disposed in excavations in ground adjacent the stove. In this stove the valve 6 is provided to regulate the oil supply to the burner 13 through the vertical supply pipe 7 and horizontal 50 pipe 8, which pipe connects with a T 9,

which is attached to a nipple 10. The nipple 10 is in turn attached to coupling 11 which carries a nipple 12 attached to the burner 13. A nipple 14 is attached to an overflow pan 14^a. The nipple 14 is attached to a coupling 15 which carries a nipple 16 attached to a T 17 and connected to the T 17 55 is a horizontal pipe 18 through which pipe the overflow oil passes at end 20 into a receptacle 19. The receptacle 19 is provided with a bail 21 with means 22 for suspending this receptacle. The main element of the invention is the damper plate 23 which is attached to the horizontal shaft 24 which shaft 60 carries a damper handle 25 at one end and locknuts 26 on threaded portions of the shaft at both ends of said shaft. The locknuts are principally for the purpose of retaining 65 the damper plate at any desired angle and elevation. The shaft 24 extends through vertically disposed slots 24^a in the stove, therefore it will be seen that the damper can be placed at different elevations in relation to the burner 13. Another important element of the invention is the threaded caps 27 and 28 applied to the lower threaded end of 70 nipples 29 and 30 and by removing these caps any sediment that may collect in the nipples and caps may be easily removed. 80

From the above it will be seen that means is provided for convenient control of the heat generated by an oil burner situated in a stove over which burner the damper is disposed and that the damper may be set at 85 different positions in relation to the burner and that by regulating the draft, the heat is radiated from the stove and utilized for heating purposes instead of a large portion of the heat passing off through the pipe or 90 smokestack. It will also be seen that the damper is smaller than the interior diameter of the stove therefore a sufficient amount of draft will be maintained at all times.

The invention having been set forth what 95 is claimed as new and useful is:—

The combination with a stove, an oil burner in the bottom of said stove, and a stove pipe, of a horizontally and rockably mounted damper within the stove above the 100 burner, said damper being smaller in diameter than the diameter of the stove, said

damper being carried by a shaft extending transversely through the stove and through vertically disposed slots in opposite sides of the stove, nuts threaded on said shaft and cooperating with the outer sides of the stove for holding the damper and shaft in various adjusted positions in relation to the

burner and a handle member carried by one end of the shaft.

In testimony whereof we affix our signatures.

JAMES M. FINNELL.
ERNEST P. GREVE.
